AUTOMOBILE VISOR

Herbert J. Fauser, Hammond, Ind.

Application May 22, 1950, Serial No. 10,083

Term of patent 3½ years

(Cl. D14—6)

To all whom it may concern:

Be it known that I, Herbert J. Fauser, a citizen of the United States, residing at Hammond, in the county of Lake and State of Indiana, have invented a new, original, and ornamental Design for an Automobile Visor, of which the following is a specification, reference being had to the accompanying drawing, forming a part thereof.

In the drawing:

Fig. 1 is a perspective view of an automobile visor, embodying my novel design;

Fig. 2 is a top plan view of the visor illustrated in Fig. 1; and

Fig. 3 is a transverse sectional view substantially through the center of the visor.

I claim:

The ornamental design for an automobile visor, as shown.

HERBERT J. FAUSER.
